CLAIM

The ornamental design for a fidget toy, as shown and described.

DESCRIPTION

FIG. 1 is a side view of the fidget toy showing my new design;

FIG. 2 is a front perspective view thereof;

FIG. 3 is an upper front perspective view thereof shown in an upright orientation; and,

FIG. 4 is a front view thereof.

The broken lines depict portions of the 'fidget toy' that form no part of the claimed design.
